R. B. MOON.
DRAFT DOOR OPENING DEVICE.
APPLICATION FILED OCT. 23, 1920.

1,382,797.

Patented June 28, 1921.

UNITED STATES PATENT OFFICE.

ROBERT BARCLAY MOON, OF PHILADELPHIA, PENNSYLVANIA.

DRAFT-DOOR-OPENING DEVICE.

1,382,797.

Specification of Letters Patent. Patented June 28, 1921.

Application filed October 23, 1920. Serial No. 419,081.

To all whom it may concern:

Be it known that I, ROBERT BARCLAY Moon, a citizen of the United States, residing at the city of Philadelphia, county of 5 Philadelphia, and State of Pennsylvania, have invented a certain new and useful Improved Draft-Door-Opening Device, of which the following is a specification.

The primary object of the present invention is to provide a time-set prime-mover for opening automatically at a predetermined period of time the draft-door of a furnace, boiler or the like, thereby obviating the necessity of manual attention for the 10 purpose. Another object of the present invention is to utilize a conventional alarm clock as a prime-mover for positively opening the draft-door of a furnace, boiler or the like, the connections employed being such 15 that but slight change to the alarm winding-arbor is the only alteration necessary in the alarm clock. A still further object of the present invention is to provide a novel form of saddle and complemental bracket for supporting the prime-mover in a position in 20 which the vertical axis thereof is out of perpendicular thereby reducing to a minimum the possibility of dust and dirt collecting upon the working parts of the prime-mover 25 at the rear thereof.

Other objects of this invention not at this time more particularly enumerated will be clearly understood from the detailed description of the invention.

30 The invention consists of the improvements hereinafter described and finally claimed.

The nature, characteristic features and scope of the invention will be more fully understood from the following description taken in connection with the accompanying drawings forming part hereof, and in which:

Figure 1, is a view in front elevation of a furnace equipped with a draft-door opening device embodying features of the invention.

Fig. 2, is a view in side elevation of the prime-mover and its support detached.

Fig. 3, is a fragmentary view, partly sectioned, illustrating a detail of construction.

Fig. 4, is a rear view thereof, and

Fig. 5, is a top or plan view of the saddle shown in Fig. 2.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings 10 designates a furnace, which may be of any desired type, provided with a draft-door 11 hinged to be moved in an outwardly and upwardly direction. 12 designates a prime-mover, for instance an alarm-clock of conventional design in which the alarm-arbor 12' is provided with a winding-key 13. In practice I slightly alter the alarm-clock by adding to the winding-key 13 a dished member 14 provided with apertures 15 and 16. The member 14 is positioned in the following manner. I first unscrew the winding-key 13 from its arbor 12', insert the stem of said key through opening 15 of member 14 and replace the winding-key upon the alarm-arbor. The convexed face of the dished member is presented to, but spaced from, the rear wall of the clock as clearly illustrated in Figs. 2 and 3 for a purpose to presently appear.

Thus positioned the finger-piece of the winding-key is contained within the recessed portion of said member. Connecting the winding-key 13 and a lug 11' on the draft-door 11 is a cable 17 of suitable material. The cable 90 is attached to the winding-key in the following manner. One end of the cable is tied to the finger-piece of the winding-key, as at 18, and the other end passed through aperture 16 of member 14, the cable being then wound in a clock-wise direction for several turns around the winding-stem as shown in Fig. 3, after which the cable end is secured to the lug 11' of the draft-door 11. While the clock may be supported in any desired manner I have devised a novel form of saddle and bracket for supporting the same.

The clock may be supported by the furnace, as shown in Fig. 1, or it may be supported from rafters overhead or in any other suitable manner. The saddle, which is designated 19, is shaped and proportioned not only to efficiently support the clock but to be capable of being packed in the same box with the clock for shipping purposes. The saddle comprises a member formed upon an 10 arc of a circle so as to conform to the contour of a clock. The opposite sides of said member each terminate in an ear 20 apertured as at 21. In practice I unscrew the feet of the clock and drill the holes 21 of 15 the saddle so as to register with the holes in the clock from which the feet have been removed, it being understood that the clock is seated within the saddle as shown in Fig. 2. I then secure the clock to place by means of 20 screws 22. Extended rearwardly from the saddle-part is an apertured lug 23 which is disposed intermediate said ears. The saddle is an integral structure. An angular bracket 24 supports the saddle, the lower arm thereof 25 being secured to the lug 23 as by a screw 25 passing through the aperture thereof. The lower arm of the bracket is inclined slightly upwardly so that the lug 23 of the saddle and said arm are disposed in parallelism, 30 when secured together. The arm and lug are arranged at such an angle that the vertical axis of the clock, as supported in said saddle, is out of perpendicular as clearly shown in Fig. 2. This is so that dust and 35 dirt will have the tendency to be deflected from the clock in contradistinction to settling thereon.

The above described parts operate in the following manner: The attendant in charge 40 of the furnace sets the time-piece to operate the alarm at the desired time of day and winds the usual time-key and the alarm-key. When the alarm operates the cable 17 is wound around the stem of the winding-key 45 between the rear of the clock and the convexed surface of the member 14, and draws outwardly and upwardly draft-door 11. In winding of the cable the convexed surface of member 14 serves to prevent the cable from 50 slipping off the winding key, the said surface having the tendency to deflect the cable as wound toward the rear wall of the clock. Of course when the alarm-key is re-wound the cable unwinds to permit the draft-door 55 to close.

According to the above construction of parts I am enabled to provide an exceedingly simple, efficient, reliable and comparatively inexpensive draft-door opener. The 60 clock, saddle, bracket and cable can be compactly arranged for transportation and installation of the parts may be readily accomplished in a few minutes time by unskilled labor.

65 It will now be apparent that I have de-

vised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages. 70 75

What I claim is:

1. In combination a supporting structure, 80 an angular bracket secured thereto the lower arm of which is disposed at an acute angle to the upper arm of the bracket, a saddle to receive a time-set prime mover carried by said lower arm which saddle is formed upon an arc of a circle and so shaped as to provide oppositely disposed ears, the seat of said saddle being arranged in a plane paralleling the plane of said lower arm, a time-set prime mover seated within said saddle and resting upon said seat and means for securing said time-set prime mover with respect to said ears. 85 90

2. In combination a supporting structure, 95 an angular bracket secured thereto the lower arm of which is disposed at an acute angle to the upper arm of the bracket, a saddle to receive a time-set prime mover carried by said lower arm, which saddle comprises an integral member formed upon an arc of a circle and provided with an ear upon each 100 side thereof, the seat of said saddle being arranged in a plane paralleling the plane of said lower arm, a time-set prime mover seated within the saddle and resting upon said seat and means for securing said time-set prime mover with respect to said ears so that the vertical axis of said time-set prime mover is out of perpendicular. 105

3. A saddle for a time-set prime-mover comprising an integral member formed upon 110 an arc of a circle and provided with an apertured ear upon each side thereof and with a downwardly inclined lug at the rear thereof disposed intermediate said ears and an angular bracket for supporting said saddle the 115 lower arm of which is in a plane paralleling the plane of the seat of said saddle.

4. A saddle for a time-set prime mover comprising a member formed upon an arc of a circle and provided with ears upon each 120 side thereof said member also being provided with an attaching lug and an angular bracket secured to said lug the arms of said bracket being disposed at an acute angle to one another with the seat of the saddle 125 paralleling the plane of the arm to which said lug is attached.

5. A construction of the character stated comprising a perpendicularly disposed arm the lower end of which terminates in an out- 130

wardly and upwardly disposed extension, a saddle to receive a time-set prime mover carried by the free end of said extension said saddle comprising a member formed upon 5 an arc of a circle and provided upon opposite sides thereof with an ear the plane of the seat of said saddle paralleling the plane

of said extension, a time-set prime mover seated within said saddle and resting upon said seat and means for securing said time-set prime mover with respect to said ears. 10

In testimony whereof, I have hereunto signed my name.

ROBERT BARCLAY MOON.
